(57) **CLAIM**

The ornamental design for a luggage with a vertically expandable shelf system, as shown and described.

DESCRIPTION

FIG. 1 is a front top right-side perspective view of an article of luggage having a vertically expandable shelf system depicted in an open configuration with the shelf system expanded in accordance with the present invention; FIG. 2 is a front top perspective view thereof;

FIG. 3 is a bottom rear left side perspective view thereof;

FIG. 4 is a top view thereof;

FIG. 5 is a bottom view thereof;

FIG. 6 is a left side view thereof;

FIG. 7 is a right side view thereof;

FIG. 8 is a front view thereof;

FIG. 9 is a rear view thereof;

FIG. 10 is a front top right side view of the article of luggage in the closed configuration;

FIG. 11 is a front bottom right side view thereof;

FIG. 12 is a top view thereof;

FIG. 13 is a bottom view thereof;

FIG. 14 is a right side view thereof;

FIG. 15 is a left side thereof;

FIG. 16 is a front view thereof;

FIG. 17 is a rear view thereof;

FIG. 18 is a front right hand perspective view thereof with the front/top flap open and the shelf system in a non-expanded configuration;

FIG. 19 is a front top left hand perspective view thereof; and, FIG. 20 is a right side rear view perspective view thereof.

The broken lines illustrate stitching and form no part of the claimed design.
